UNITED STATES PATENT OFFICE.

MILO BROWN, OF WELLINGTON, TEXAS, ASSIGNOR OF ONE-HALF TO WILLIAM B. KIRBY, OF WELLINGTON, TEXAS.

PIPE-CLAMP.

1,153,024.

Specification of Letters Patent.

Patented Sept. 7, 1915.

Application filed May 27, 1913. Serial No. 770,222.

To all whom it may concern:

Be it known that I, MILO BROWN, citizen of the United States, residing at Wellington, in the county of Collingsworth and 5 State of Texas, have invented new and useful Improvements in Pipe-Clamps, of which the following is a specification.

This invention relates to pipe clamps and more particularly to the gripping jaws thereof which are so arranged as to have the gripping surfaces of one jaw arranged 10 to one side of the pivotal connection of the opposite jaw. This last mentioned gripping surface acts as a fulcrum point for immediately throwing the gripping surfaces of 15 the opposite jaw into engagement with the pipe.

The invention in the preferred form of details will be described in the following 20 specification, reference being had particularly to the accompanying drawings, in which:—

Figure 1 is a view in side elevation of the improved machine. Fig. 2 is a vertical central section. Fig. 3 is a perspective view of the movable gripping element including the spaced jaws.

Referring particularly to the accompanying drawings the improved machine comprises a base 1 preferably in the form of a plate designed to rest upon the surface of the platform or ground adjacent the well and formed in one edge with a recess 2 to permit the passage of pipe through the base 30 in the raising or lowering operation thereof. Secured to and rising from the base are spaced parallel uprights 3, said uprights being of any appropriate height and substantially constructed to withstand the 35 strain to which the machine is subjected in use.

Removably mounted upon a pivot bolt 4 joining the standards near their upper ends is an operating lever 5, preferably of angle 45 form, the long end of which constitutes the handle end. A link 6 is pivotally connected to the short end of the lever and in turn pivotally supports the upper gripping member 7. This member comprises spaced parallel bars 8 turned toward each other at their rear ends and terminally formed with rearwardly extending contacting ears 9 to which the link or links are pivotally connected.

The bars 8 which are spaced apart at their forward ends are connected by a pivot rod 55 10 on which is mounted a gripping element 11 including a plate-like strip 12 rotatably mounted on the pivot and corresponding in width to the distance between the bars 8. At the respective upper and lower ends said 60 strip is formed or provided with jaws 13 and 14, said jaws extending practically at right angles to the strip and inwardly thereof. The upper jaw 13 has its free edge formed on inwardly diverging lines as at 65 15 while the lower jaw 14 has its free or gripping edge 16 straight, the gripping edges of both jaws being preferably sharpened. Secured to and bridging the bars 8 at the ends remote from the connection of 70 the gripping element 11 thereof is the fixed gripping element 17 formed of a strip passed across the upper edges of the bars and turned downwardly in contact with their outer surfaces and riveted in place. 75 That portion of this strip between the bars is formed with a gripping edge 18 arranged on inwardly converging lines and sharpened. The length of the strip 12 of the gripping element 11 is such that the jaws 13 and 14 80 are above and below the jaw or gripping edge 18 of the fixed element 17. Mounted between the uprights 3 below the upper gripping element 7 is the lower gripping element 19. This element is preferably in 85 the form of a lever 20 mounted upon a pivot pin 21 arranged to coöperate within one of the series of longitudinally aligned openings 22 in the uprights, whereby the lower gripping element is longitudinally adjustable 90 with respect to said uprights. The rear end of the lever 20, or that portion projecting on the same side of the uprights as the handle of the operating lever 5 is bent to form a 95 foot operating extension 23, and intermediate said foot extension and the pivot is connected to the uprights by a spring 24 whereby the rear end of the lever is normally maintained elevated.

The forward portion of the lever 20 is 100 formed to provide a spaced parallel bar 25, corresponding in size and shape to the bars 8 of the upper gripping element. Between the bars 25, and at their forward ends is pivotally supported a movable gripping element 26 similar in all respects to the grip-

ping element 11 of the upper gripping member. Said bars 25 are further provided with a fixed gripping element 27 corresponding in all respects to the fixed gripping element 17 of the upper member.

In operation, as will be apparent from the drawings the pipe is passed vertically between the fixed and movable gripping elements of the lower gripping member and 10 between the similar elements of the upper gripping member. In this position the fixed jaws of both gripping members will coöperate, assuming the pipe is to be lifted with the upper jaws of the movable gripping 15 elements of each member, so that the pipe will be initially held by the inwardly convergent gripping edges of said jaws. As the operating lever is lowered the upper gripping element is in effect moved outwardly causing the movable gripping element 11 to more tightly force the pipe against the fixed jaw 18, the upward movement of the pipe freeing the movable element 26 of the lower gripping member from 20 a gripping action on the pipe incident to the pivotal mounting of said element 26. When the lever is released and moved downwardly for a new grip the spring 24 forces the forward end of the lever 20 downwardly with 25 the effect to force the upper jaw of the gripping element 26 of the lower member into gripping coöperation with the pipe holding the pipe against the fixed jaw 27. A repetition of this operation causes the pipe to be gradually elevated to the desired extent. In lowering the pipe the upper gripping member is the medium for gripping the pipe during the release of the lower gripping member, said latter member in this instance

being operated by foot pressure upon the 40 foot extension 23 of said lever 20.

The detailed formation of the jaws of the respective movable and fixed gripping elements is particularly important in that it prevents the slipping of the pipe and insures a firm hold thereon under all conditions. The pivotal mounting of the movable gripping elements 11 and 26 are further important as it compels a comparatively extensive movement of the elements for the 45 gripping operation while at the same time affording sufficient space for the passage of couplings or the like on the pipe in the release position of said movable gripping elements.

It is of course to be understood that the various parts are to be constructed of such material and in such relative sizes as will best adapt them for the particular character of pipe being operated upon, and that 50 aside from the essential details hereinabove described, I in no wise limit myself as to shape, size or material of the parts.

What is claimed is:—

A pipe grip comprising a pair of spaced 55 bars, a strip pivoted at a point adjacent to the extremities of said bars, said strip having its ends bent at right angles to form gripping surfaces, and a grip element secured to the bars and having its gripping 60 surface positioned to one side of the pivotal connection of said strip.

In testimony whereof I affix my signature in presence of two witnesses.

MILO BROWN.
